UNITED STATES PATENT OFFICE

CHARLES P. SCHLEGEL, OF ROCHESTER, NEW YORK, ASSIGNOR TO THE SCHLEGEL MANUFACTURING COMPANY, OF ROCHESTER, NEW YORK, A CORPORATION OF NEW YORK

FINISHING STRIP FOR UPHOLSTERY

Application filed October 23, 1930. Serial No. 490,666.

The present invention relates to finishing strips for upholstery and an object of the invention is to provide a construction which will hide the nail heads while being easily and quickly applied. Another object of the invention is to provide a nail head concealing molding or finishing strip without any movable cover for the nail head.

To these and other ends, the invention consists of certain parts and combinations of parts all of which will be hereinafter described: the novel features being pointed out in the appended claims.

In the drawing:

16 Fig. 1 is a perspective view of a molding or finishing strip embodying the present invention;

18 Fig. 2 is a transverse section through the molding shown in Fig. 1; and

20 Fig. 3 is a transverse section through another embodiment of the invention.

In carrying out the invention it is preferred to employ a nail holding strip in the form of a cloth or wire fabric 1 coated with 25 rubber 2. Over this nail holding strip is arranged a nail head concealing means preferably in the form of an outside woven fabric covering 3 secured at opposite edges by cement to the under side of the nail holding 30 strip and enclosing a strip of resilient material 4 which offers less resistance to the passage of a small headed nail or tack 5 therethrough than does the nail holding strip 2 which can be struck by a hammer 35 and will return to normal shape or condition except for a small hole made by the nail, this hole being partially rendered invisible by the expansion of the material and being wholly rendered invisible by the woven 40 fabric covering which is substantially unaffected by the passage of a nail therethrough.

In the embodiment of the invention shown in Figs. 1 and 2 the resilient strip 4 45 is made of sponge rubber so that when the

nail 5 is driven into the molding the head of the nail passes entirely through the fabric covering and the sponge rubber 4 and comes to rest against the nail holding strip.

In the embodiment shown in Fig. 3, the 50 resilient strip 4^a is formed by a section of a tube of soft rubber, and the nail passes through the fabric 3 and the tube section and into the nail holding strip 1, 2. This construction provides a channel on the under 55 side of the soft rubber strip which adds to the resiliency of the latter and causes the rubber to spring away from the nail head after the nail has been driven therethrough.

In using the molding or finishing strip, a 60 nail or tack with a small head is driven into the molding through the outer textile fabric and the yielding strip, the hammer compressing the soft yielding strip which permits the nail head to pass therethrough until the head engages the holding strip 1, 2 65 when the progress of the nail is stopped. The yielding material springs back and the hole therein is practically closed while that in the fabric is invisible due to the fact that 70 the yielding strip acts to readjust the strands of the fabric. In other words the nail holding portion is covered by a self closing means for the holes made by a nail passing therethrough.

75 What I claim as my invention and desire to secure by Letters Patent is:

1. A finishing strip comprising a nail holding strip, a resilient strip having less nail holding quality than the first named 80 strip, and a woven fabric covering securing said strips together and through which the nail heads are sunk.

2. A finishing strip comprising a nail holding strip, and a soft rubber strip secured over said nail holding strip and through which the nail heads are driven and sunk against said holding strip.

3. A finishing strip comprising a nail holding strip, and a strip of resilient mate-

rial secured over the nail holding strip and having a channel in its under side affording a clearance space between said material and said holding strip.

- 5 4. A finishing strip comprising a nail holding strip, a strip of resilient material overlying said nail holding strip and having an initially imperforate surface through which the nail heads are sunk against said holding strip, and a woven fabric covering securing said strips together and adapted to close over the said nail heads.

CHARLES P. SCHLEGEL.
